His attorney.

UNITED STATES PATENT OFFICE.

OTTO C. ROHDE, OF TOLEDO, OHIO, ASSIGNOR TO CHAMPION SPARK PLUG COMPANY, OF
TOLEDO, OHIO, A CORPORATION OF DELAWARE.

SPARK-PLUG.

1,313,419.

Specification of Letters Patent.

Patented Aug. 19, 1919.

Application filed April 22, 1918. Serial No. 230,114.

To all whom it may concern:

Be it known that I, OTTO C. ROHDE, a citizen of the United States, and a resident of Toledo, in the county of Lucas and State 5 of Ohio, have invented a certain new and useful Spark-Plug; and I do hereby declare the following to be a full, clear, and exact description of the invention, such as will enable others skilled in the art to which it 10 appertains to make and use the same, reference being had to the accompanying drawings, and to the characters of reference marked thereon.

This invention relates to spark plugs for 15 internal combustion engines, and particularly to spark plugs of the heavy duty type.

The object of my invention is the provision of a spark plug having its insulator built up in such manner as to prevent or 20 reduce to a minimum the liability of short circuiting the electric ignition circuit through any part of the insulator, thereby particularly adapting the plug for use in high speed motors, or for heavy duty purposes. 25

The invention is fully described in the following specification, and a central longitudinal section of a spark plug embodying the same is illustrated in the accompanying 30 drawing.

Referring to the drawing, 1 designates the shell or casing of a spark plug, which shell is provided with the customary threaded nipple 2 at its inner end and with 35 the annular internal reducing shoulder 3 adjacent to the inner end of the nipple 2 and with the annular internal shoulder 4 at the outer end of the nipple. 5 is the customary electrode, which is grounded 40 through the shell or casing, and 6 is the center electrode which may be of nickel, manganese, or other suitable material and is carried by the current conducting spindle 7 projecting axially through the shell and 45 preferably provided with an enlargement 8 forming an annular shoulder at its inner or electrode carrying end to which the electrode 6 is attached if the electrodes and spindle are made in separate pieces. The 50 spindle 7 is rigidly carried within the shell 1 and effectively insulated therefrom by an insulator, the construction and arrangement of the parts of which will now be described.

An insulator sleeve 9 of tubular form 55 and preferably comprising a plurality of

thin cylinders or tubes of mica or other suitable insulating material, closely fitted one within another, is fitted closely within the shell and extends from the shoulder 3 to adjacent to the outer end of the shell. 60 A similar sleeve 10 is fitted closely within the nipple 2, extending inward from the shoulder 4 a distance beyond the shoulder 3 in lapping relation to the adjacent end of the sleeve 9 but radially spaced therefrom. 65 An insulating sleeve 11, similar in construction to the sleeves 9 and 10, closely embraces the spindle 7 and extends from near the outer end of the spindle to near the enlargement 8 thereon, but preferably in longitudinally spaced relation to such enlargement and a short distance within the inner end portion of the sleeve 10 in radially spaced relation thereto. A tubular insulating lining 12, preferably, but not necessarily composed of mica, is fitted closely within the sleeve 10 and extends from the shoulder 4 to the end of the center sleeve 11 in close end abutment with each. The inner end portion of this lining completely fills the 80 space between the spindle 7 and sleeve 10 from the sleeve 11 to the spindle enlargement or shoulder 8 and thence has its opening enlarged to receive the spindle or chamber 13 around the electrode. A tubular 85 lining member 14, preferably built up in laminated form of mica washers, is fitted between the sleeves 9 and 11 and extends from the outer end of the sleeve 9 substantially flush therewith to the inner end of the sleeve 10 on which it seats and is provided at such inner end with the two annular leg portions 15 and 16, the former fitting within the space between the adjacent end portions of the sleeves 10 and 90 11 and against the inner end of the lining member 12; and the latter fitting within the space between the adjacent end portions of the sleeves 9 and 10 and seating on the shoulder 3. 95

A metal collar 17 which may be of steel, brass or other suitable material, is preferably fitted within the outer end portion of the shell 1 around the spindle sleeve 11 and against the adjacent ends of the sleeve 9 and lining member 14. This collar forms a firm seat over which the outer edge portion 18 may be turned to retain the insulator parts within the shell in rigid assembled relation. A sleeve 19 of insulating material, which may 110

- comprise a plurality of mica washers built up in laminated form, encircles the outer end portion of the sleeve 11 without the collar 17 and extends from such collar to a point 5 slightly beyond the outer end of the sleeve 11, where it receives the thrust of a binding nut 20 through the medium of a washer 21, said nut being threaded on the outer end portion of the spindle.
- 10 A lock nut 22 is threaded on the spindle 7 without the nut 20 and a terminal binding nut 23 is threaded on the spindle without the nut 22 to coöperate therewith to bind a wire terminal.
- 15 It is evident that the forcing of the shell edge 18 over on the outer edge of the thrust collar 17 exerts a longitudinal thrust through said collar and on to the interior insulating parts, with the exception of the 20 sleeve 11, and forces the laminations of the members 12, 14, 15 and 16 closely together and against the respective abutting shoulders 3 and 4 of the shell, and that the tightening of the jam nut 20 on the spindle 7 25 forces the insulating member 19 against the collar 17, and at the same time exerts an outward pull on the spindle 7 to tighten its enlargement 8 against the shouldered portion of the insulating member 12.
- 30 It is also evident that the sleeve 9 laps the inner end of the sleeve 11 and that the sleeve 10 laps the inner ends of both the sleeves 9 and 11, thus preventing any possibility of a short circuit taking place between the shell 35 and spindle around the ends of said sleeves through spaces which may occur between some of the lamina of the insulating members 12, 14, 15 and 16. It is found in practice that this plug is highly efficient for use in 40 high speed or heavy duty motors in which considerable trouble has been experienced by reason of short-circuiting taking place between the shells and spindles of the spark plugs.
- 45 While I have particularly referred to laminated mica as being used as the insulating material, the invention is not restricted to the use of such material, as it contemplates the use of any other suitable insulating material, whether of solid or laminated form.
- I wish it understood that my invention is not limited to any specific form or arrangement of the parts, as it is capable of numerous modifications without departing 55 from the spirit of the claims.
- Having thus described my invention, what I claim as new and desire to secure by Letters Patent, is:—
1. In a spark plug, a shell, an electrode spindle passing through the shell, and an insulator carrying the spindle and having an insulator sleeve fitting the spindle, separate insulator sleeves fitting different portions of the shell, said sleeves extending longitudinally of the spindle and lapping
- each other in radially spaced relation, and insulator members disposed between said sleeves and coöperating therewith to insulate the spindle from the shell.
2. In a spark plug, a shell having its bore reduced at the electrode end, an electrode spindle passing through said shell, and an insulator carrying such spindle, said insulator having within the shell three longitudinally extending sleeves which fit the 75 spindle and the different portions of the shell in lapping relation one to another, and insulator members coöperating with said sleeves to insulate the spindle and shell.
3. In a spark plug, a shell having a plurality of shoulders, an electrode spindle passing through said shell and having an enlargement within the electrode end portion of the shell, and an insulator carrying said spindle, said insulator having within 80 the shell three longitudinally extending insulating sleeves some of which seat on said shoulders and having insulating filling members seating on said shoulders and spindle enlargement and coöperating with said 85 sleeves to insulate the spindle and shell, said sleeves lapping each other in radially spaced relation.
4. In a spark plug, a shell having internal shoulders, an electrode spindle passing 90 through said shell and having an enlargement adjacent to its electrode end, an insulator rigidly connecting said spindle and shell, said insulator having an insulating sleeve fitting the spindle and extending from 95 without the outer end of the shell to adjacent to the spindle enlargement, insulating sleeves fitting different portions of said shell and lapping each other and the inner end of 100 said spindle sleeve, insulating means filling the spaces between said sleeves and coöperating 105 therewith to insulate the shell and spindle, a thrust member disposed in the outer end portion of the shell, and engaged by the shell to coöperate therewith to retain the 110 interior insulating sleeves and members in assembled relation and seated on the shoulders, an insulating collar without said thrust member encircling the outer end of said spindle sleeve, and means on the outer end 115 of the spindle coöperating therewith and with the spindle enlargement to secure the insulator parts in assembled relation on the spindle.
5. In a spark plug, a shell, having a reduced nipple at its inner end and provided with internal shoulders adjacent to the inner and outer ends of said nipple, an electrode spindle passing through said shell, an insulating sleeve fitting within the large portion 120 of the shell and extending from the inner one of said shoulders adjacent to the outer end of the shell, a second insulating sleeve 125 fitted within the shell nipple and extending from the outer one of said shoulders to a dis-

- tance beyond the inner shoulder in lapping relation to said first sleeve, a third insulating sleeve fitting said spindle and extending from adjacent the outer end of the spindle 5 to adjacent the inner shoulder of the shell and in lapping relation to both said first and second mentioned sleeves, insulating filling members coöperating with said sleeves to insulate the spindle from the shell, a thrust 10 member fitted within the outer end portion of the shell and coöperating therewith to force said first and second sleeves and said filling members against respective shoulders within the shell, an insulating collar encircling the spindle sleeve without said thrust member, and means on the spindle for clamping it to the insulating members mounted thereon.
6. In a spark plug, a shell, having an internally reduced nipple at its inner end and provided with internal shoulders adjacent to the inner and outer ends of said nipple, an electrode spindle passing through said shell, 20 an insulating sleeve fitting within the large portion of the shell and seating at its inner end on the inner shoulder, a second insulating sleeve fitting within the nipple and extending from the outer one of said shoulders to a distance beyond the inner shoulder in 25 radially spaced lapping relation to said first
- sleeve, a third insulating sleeve fitting said spindle and having its inner end extending beyond the inner end of said second sleeve in radially spaced lapping relation thereto, insulating filling means filling the spaces between said sleeves, and means coöperating with the spindle to secure said sleeves and filling means in assembled relation. 35
7. In a spark plug, a shell, having its bore reduced at its inner end and provided with internal shoulders at the inner and outer ends of the reduced portion, a spindle extending through said shell, separate insulating sleeves fitting within the large and reduced portions of said shell with their adjacent ends in radially spaced lapping relation, an insulating sleeve fitting said spindle with its inner end in lapping relation to the inner end of the sleeve which is fitted into the small portion of the shell, insulating 40 means filling the space between said sleeves and also forming a facing means for the inner side of the sleeve which fits into the small portion of the shell bore, and means for securing said insulating parts in assembled relation. 45
- In testimony whereof, I have hereunto signed my name to this specification.

OTTO C. ROHDE.
